(57) **CLAIM**

The ornamental design for a display screen or portion thereof with an animated graphical user interface, as shown and described.

DESCRIPTION

FIG. 1 is a front view of a first image of a first embodiment of a display screen or portion thereof with an animated graphical user interface showing our new design; FIG. 2 is a front view of a second image thereof; FIG. 3 is a front view of a third image thereof; FIG. 4 is a front view of a fourth image thereof; FIG. 5 is a front view of a first image of a second embodiment of a display screen or portion thereof with an animated graphical user interface showing our new design; FIG. 6 is a front view of a second image thereof; FIG. 7 is a front view of a third image thereof; and, FIG. 8 is a front view of a fourth image thereof.

In the first embodiment, the appearance of the transitional image sequentially transitions between the images shown in FIGS. 1 through 4. In the second embodiment, the appearance of the transitional image sequentially transitions between the images shown in FIGS. 5 through 8. The process or period in which one image transitions to another image forms no part of the claimed design.

The dash-dot broken line showing of a portion of a display screen in FIGS. 1-8 represents environmental subject matter and forms no part of the claimed design.
